UNITED STATES PATENT OFFICE

2,192,999

PHONOGRAPHIC APPARATUS

Emile C. Guedon, Audubon, N. J., assignor to Radio Corporation of America, a corporation of Delaware

Application January 31, 1938, Serial No. 187,935

4 Claims. (Cl. 274—1)

This invention relates to phonographic apparatus, and more particularly to a combined pick-up locating and needle-gauging device.

For uniform results in the reproduction of sound from phonograph records by means of a pick-up device having a needle socket and a reproducing needle carried therein, it is desirable that each needle should extend from the needle socket the same distance. The primary object 10 of my present invention is to provide a needle-gauging device which will insure each new needle extending from the needle socket in this manner.

More specifically, it is an object of my present 15 invention to provide an improved device of this type which will accurately locate the pick-up device with respect to the needle gauge so that each needle will be gauged correctly automatically upon the pick-up device being properly located.

Another object of my invention is to provide 20 an improved device as aforesaid which will permit the facile ejection of used needles.

It is also an object of my present invention to 25 provide an improved device of the type set forth which is simple in construction, economic in cost, and highly efficient in use.

In accordance with my present invention, I 30 place a used needle receptacle on the motor board of the phonograph and provide a movable cover therefor at a suitable height thereover. The receptacle is also provided with means for locating the pick-up device in proper relation to the movable cover which is adapted to act as a gauge for each new needle. This invention 35 is particularly suitable for pick-ups of the "top loading" type wherein the new needles are inserted through an opening in the top of the pick-up, such as described in my copending application Serial No. 177,293, filed November 30, 1937.

40 By merely placing the pick-up device on the aforesaid locating means and permitting a needle to slip into the socket through an opening in the top of the pick-up, the needle will, upon hitting the cover, be automatically and properly gauged in the needle socket, whereupon the needle holding screw may be tightened. After 45 sufficient use, and prior to inserting a new needle, the pick-up is again placed on the aforesaid locating means, the needle screw is loosened, and the cover is swung away from the needle to permit the used needle to drop into the receptacle. A suitable spring automatically returns the cover to gauging position when the cover is released, and a new needle may then be inserted and locked 50 in place.

The novel features that I consider characteristic of my invention are set forth with particularity in the appended claims. The invention itself, however, both as to its organization and method of operation, together with additional 5 objects and advantages thereof, will best be understood from the following description of one embodiment thereof, when read in connection with the accompanying drawing, in which

Figure 1 is a view showing the relation of a 10 pick-up device with the locating and gauging device according to my invention.

Figure 2 is a plan view of the combined pick-up 15 locating and needle-gauging device turned 180° from the position shown in Fig. 1.

Figure 3 is a side elevation thereof as seen from the right in Fig. 2, and

Figure 4 is a section taken on the line IV—IV of Fig. 2.

Referring more particularly to the drawing, 20 wherein similar reference characters designate corresponding parts throughout, there is shown a motor board 1 having a discharge opening 3 into which is fitted my improved pick-up locating and needle-gauging device. This comprises 25 a frame 5 from which depends a needle receptacle 7 adapted to receive used needles. The receptacle 7 is provided with a plurality of extensions 9 having aligned openings through which a pin 11 extends, a C washer 13 holding the pin 11 30 against removal from the extensions 9.

Pivotedly mounted on the pin 11 by means of its downwardly extending arms 15 is a gauge plate 17 which acts as a cover for the receptacle 7, the cover 17 being constantly urged to the 35 closed position shown in Fig. 1 by means of a coil spring 19 and having a finger piece 21 by means of which it may be grasped and moved manually to open position in the direction of the arrow appended to Fig. 1, or from the solid line 40 position to the dotted line position of Fig. 4.

Extending upwardly from the frame member 5 are a pair of posts 23 and 25 for locating a pick-up device 27 with respect to the cover or gauge 17. The posts 23 and 25 extend above the receptacle 7 a distance greater than the height of the cover 17 above the receptacle when in closed position, and the post 23 may be notched, as at 29, to receive one edge of the frame of the pick-up 27 so that the pick-up will not move about when 50 once located with respect to the gauge 17. The post 25 may be employed merely to help support the pick-up 27 in the desired position.

When the pick-up 27 is placed on the locating posts 23 and 25, a needle 31 may be inserted 55

through an opening 33 in the top of the pick-up to slide freely down into the socket 35, the needle coming to rest when it hits the cover or gauge 17. This automatically determines the extent to 5 which the needle 31 will protrude from the socket 35, and the needle screw 37 may then be tightened to hold the needle 31 in place. After the needle 31 has been used as much as necessary, the pick-up 27 is placed upon the locating posts 10 23 and 25, the needle screw 37 is loosened, and the cover 17 is manually moved to the dotted line position of Fig. 4 by pushing the finger piece 21 downwardly and swinging the cover 17 in the direction of the arrow shown in Fig. 1. This permits the used needle to slip down into the receptacle 7. Upon releasing the cover 17, the spring 19 forces it back to closed position, whereby a new needle may be inserted through the opening 33 and the procedure described above followed 15 again. When needles having a lacquered shank are employed, they sometimes stick in the needle socket 35. The cover 17 is so mounted on the pin 11 that, when the finger piece 21 is depressed, the opposite edge of the cover 17 is first slightly 20 raised to effect a camming action upon the used needle and force it upwardly in the socket 35 a slight distance. This loosens the needle sufficiently to permit it to drop freely into the receptacle 7 when the cover 17 has cleared it. 25

30 Although I have shown and described but one embodiment of my invention, it will be apparent to those skilled in the art that many other modification thereof are possible. For example, if desired, the receptacle 7 may be omitted and the 35 gauge plate 17 pivoted on the motor board 1 at the walls defining the discharge opening 3, so that, when the plate 17 is moved in the direction of the arrow in Figure 1, the needle may drop directly through the opening 3. Other changes 40 will, no doubt, readily suggest themselves to those skilled in the art. I therefore desire that my invention shall not be limited except insofar as is made necessary by the prior art and by the spirit of the appended claims.

45 I claim:

1. In a phonograph of the type employing a pickup device having a needle socket and a reproducing needle carried in said socket, the combination therewith of a member having an opening therein, a gauge plate pivotally mounted on 50 said member over said opening and movable to

and from gauging position over said opening, and a pickup supporting device for locating said pick-up relative to said gauge plate, said supporting device being disposed adjacent said plate and extending thereabove whereby, when said pickup is placed on said supporting device and said gauge plate is in gauging position, said gauge plate will gauge the needle in said socket. 5

2. In a phonograph of the type employing a pickup device having a needle socket and a reproducing needle carried in said socket, the combination therewith of a member having an opening therein, a gauge plate pivotally mounted on said member over said opening and movable to and from gauging position over said opening, a pickup supporting device for locating said pick-up relative to said gauge plate, said supporting device being disposed adjacent said plate and extending thereabove whereby, when said pickup is placed on said supporting device and said gauge plate is in gauging position, said gauge plate will gauge the needle in said socket, and means associated with said gauge plate constantly urging said gauge plate to needle gauging position over said opening. 10 20 25

3. In a phonograph of the type employing a pickup device having a needle socket and a reproducing needle carried in said socket, the combination therewith of a member having an opening therein, a gauge plate pivotally mounted on said member over said opening and movable to and from gauging position over said opening, a pickup supporting device for locating said pickup relative to said gauge plate, said supporting device being disposed adjacent said plate and extending thereabove whereby, when said pickup is placed on said supporting device and said gauge plate is in gauging position, said gauge plate will gauge the needle in said socket, means associated with said gauge plate constantly urging said gauge plate to needle gauging position over said opening, and a finger piece on said gauge plate adapted to be manually grasped to move said plate clear of the needle whereby to enable said needle to drop through said opening. 30 35 40 45

4. The invention set forth in claim 3 characterized in that said gauge plate is so formed as to first effect a camming action upon the needle prior to clearing the needle to permit it to drop through said opening. 50
